OVERALL POCKET

Filed Dec. 16, 1924

INVENTOR:
Edward I. Krumpelbeck

BY John Elias Jones

ATTORNEY.

UNITED STATES PATENT OFFICE.

EDWARD I. KRUMPELBECK, OF CINCINNATI, OHIO, ASSIGNOR TO THE GLOBE OVER-
ALL COMPANY, OF CINCINNATI, OHIO, A CORPORATION OF OHIO.

OVERALL POCKET.

Application filed December 16, 1924. Serial No. 756,311.

This invention relates to overall-pockets and, more particularly, to those adapted for special use in holding a measuring-rule in convenient position on the outer face of the 5 trousers or other desired garment, and the principal object of the invention herein is to provide in addition to said measuring-rule receptacle or pocket an adjunct or immediately-coupled pocket that forms a substantial and helpful part thereof in order 10 to hold or contain, or to easily accommodate, one or more additional useful articles, such as pencils, screw-drivers, marking-chalk, twine and the like that are common 15 for the workman and without interfering in the least with the presence of the said measuring-rule, or, for that matter, any of the articles in the combined pockets, or double-compartment pocket, interfering materially 20 with each other in either holding or removing them, or inserting them, as desired.

The composition or make-up of the "duplex" pocket by using but two pieces of goods and thus creating such a form of 25 pocket, by the complete rule and adjunct sections or pocket content-elements herein, will be fully and clearly described herein-after in connection with the accompanying sheet of drawings, in which—

Figure 1 is a fragment of a piece of textile overall-fabric on which is stitched my "duplex" pocket herein; Fig. 2, a plan view or diagram of the piece of goods forming the rule-section of my "duplex" or composite 30 pocket; Fig. 3, a plan view or diagram of the piece of goods forming the adjunct part of my "duplex" pocket, such piece being used in superposed position upon the lower portion of the said rule-piece in the finished 35 "duplex" pocket seen in Fig. 1; Fig. 4, a vertical section taken on the dotted-line 4, 4, of Fig. 1 showing very minutely the manner in which the parts or sectional-elements of the "duplex" pocket are assembled and 40 attached in their respective places for independent, as well as combined use; and Fig. 45 5, a horizontal section taken on the dotted-line 5, 5, of Fig. 1, showing very clearly how the rule-piece and the adjunct-piece of the two sectional-elements of the "duplex" 50 pocket herein are assembled upon and duly stitched to the goods of the garment.

A indicates a fragmentary portion of the garment goods or fabric upon which my 55 "duplex" pocket herein is placed and at-

tached for convenient use of the workman wearing said garment.

6 indicates the upper or main sectional-element of my composite pocket, and 7 the lower or adjunct sectional-element of the 60 said "duplex" pocket. These two sectional-elements are cut out in the respective outlines shown in Figs. 2 and 3, and, in assembling them for attachment to the outer face of the garment, the upper right-corner 65 8 of the said main or rule element 6 is folded inwardly on the oblique-line 9, as best seen in Fig. 2, and the upper edge 10 of said adjunct-element 7 is folded inwardly on the horizontal dotted-line 11, as best seen in 70 Fig. 3. Both of these folds are then immediately afterward stitched or hemmed at 9^a and 10^a, respectively, in place prior to the final easy-attaching of the said two sectional-elements in their next union or entirety to 75 the outer face of the garment, the upper or main part of the adjunct-element 7 being laid or lapped upon the lower part of the main part of the main or rule element 6, with the extreme lower edge of the latter 80 terminating a short distance above the bottom of the said adjunct-element 7, as shown at 12 in Fig. 4 and by a dotted-line 12 in Fig. 1. The stitching along the vertical 85 side-edges 13 and 14 and the horizontal top and bottom edges 15 and 16, respectively, is then effected to securely attach the now combined sectional-elements in using place or position on the outer face of the garment, 90 convenient for the workman in holding and handling his tools or articles of multiple use contained in the "duplex" pocket that has preferably but one bottom, as shown at 17 in both Figs. 1 and 4, that is common alike to the rule and adjunct elements thereof. 95 The curtailed lower edge 12 of the rule-element 6 saves goods and any unnecessary thickening of the lower part of the "duplex" pocket.

In use, the "duplex" pocket herein is laid 100 at a slight angle to the perpendicular, as shown in Fig. 1, and as customary in arranging rule-pockets on the outer face of overall trousers, and the rule-element is open at its side, as shown at 18 in Fig. 1, while 105 the adjunct-element is open at its upper edge or top, as seen at 19 in said Fig. 1 and, also, in Fig. 4. The extreme horizontal upper edge 15 of the said rule-element is closed 110 so as to form a cap to that pocket, and

thereby prevent rising of the objects or their removal except through the vertically-slanting side-opening 18.

It will be readily seen that my "duplex" pocket is at once very simple, very easily and cheaply made, either out of whole or scrap fabric, as desired, and extremely easy to apply to a new or to an old garment already in use, or the adjunct-element itself taken and applied to the ordinary form of rule-element that would already be on the garment but with its lower edge hemmed and stitched in secured-place on the garment to form a separate bottom for the rule and another separate bottom for the additional articles of use for the workman. Of course, the rule-element, if desired and otherwise expedient, could be continued on down into the lower hem of the adjunct-element and thus provide a partition, as it were, between the two elements clear down to the bottom of the composite pocket.

I claim:

1. A composite or "duplex" pocket for overalls comprising a main sectional element having a closed horizontal upper end and an outside adjunct sectional element partly superposed or laid upon the lower part of said main sectional element and thence extending downwardly beyond the lower edge of the said main sectional element whereby the said two overlapping sectional elements are set and attached in assembled-place on the outer face of the garment and a single bottom is provided that is used in common by both of said sectional elements herein and with an access or inlet side-opening to the main sec-

tional element and, also, with an independent access upper-opening to the said adjunct sectional element, substantially as shown and 40 described.

2. The combination with a garment, of a pocket comprising two pocket members secured to the garment in partial superposed relation with the outer of the two pocket members opening at its top and constituting an extension for and the bottom of the inner pocket and the inner of the two pockets being closed at its top and opening at its side above the outer pocket. 50

3. The combination with a garment, of a compound pocket comprising a pocket member secured to the garment at its top, one vertical edge and part of its other vertical edge thereby leaving a pocket opening at the upper portion of one vertical edge and a second pocket member arranged over said first pocket and with its upper edge below the pocket opening of said first pocket and extending below the lower edge of said first pocket and constituting an extension and a bottom for said first pocket. 55

4. The combination with a garment, of a composite pocket comprising a pocket member closed at its top and secured to the garment to provide a side pocket opening and an unattached bottom edge and a second pocket member overlapping the lower open end of said first pocket member and secured to the garment at its sides and bottom to provide a top pocket opening and to form a bottom for said first pocket member. 60 65 70

EDWARD I. KRUMPELBECK.
